UNITED STATES PATENT OFFICE.

ANDREW J. SMITH AND JASPER N. SMITH, OF PLATTEVILLE, WISCONSIN.

DRAG-SAWING MACHINE.

SPECIFICATION forming part of Letters Patent No. 258,324, dated May 23, 1882.

Application filed October 29, 1881. (No model.)

To all whom it may concern:

Be it known that we, ANDREW J. SMITH and JASPER N. SMITH, citizens of the United States of America, residing at Platteville, in the county of Grant and State of Wisconsin, have invented certain new and useful Improvements in Drag-Sawing Machines; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention has relation to portable drag-saws of that class in which two or more saws are used.

The object of this invention is to construct drag-saws of the class named which will have 20 the qualities of durability, speed to do the work quickly, and which may be carried from place to place, forming an important factor or adjunct to a farm.

Our invention consists in the novel construction and combination of parts, as will be hereinafter more fully set forth.

In the accompanying drawings, Figure 1 represents a perspective view of our improved machine. Fig. 2 is a longitudinal central sectional view of the same. Fig. 3 is a perspective view of one of the cross heads, showing portions of the attachments; and Fig. 4 is a modification of the clamping-bar.

The letter A represents the saw-frame, built 35 substantially as shown in the drawings, and provided at its forward end with wheels *a* and at its rear with handles for the purpose of lifting and moving it from place to place. On the upper surface of the side beams of the frame 40 are suitably supported the journal-bearings of the shaft B, carrying the driving-wheel and the crank-shaft C operating the saws. On the side beams, forward of the center of the frame, are fixed the uprights, for the purpose hereinafter 45 set forth. The crank-shaft C, resting in suitable journal-boxes on the side beams of the saw-frame, is provided with a cog-wheel engaging with the master gear-wheel B, and connected in turn with the cross-heads of the saws.

50 The letters D D represent the guideways in which operate the cross-heads of the saws.

These guideways rest upon and are rigidly fixed to a frame, E; or they may form a component part thereof, and their forward ends rest, when the machine is not in motion or in use, upon the upper end cross-beam of the saw-frame. The frame E is suspended or journaled to the crank-shaft, so as to be capable of being lifted at its forward end from or above the timber or stick. This frame is formed of side 55 rails and a cross-rail at the forward end of the frame.

The letters F F' (see Figs. 1 and 3) represent the cross-heads of the saws, connected with the crank-shaft by means of the draw-bars or pitmen *d*, and held in the guideways by means of the side flanges of the cross-heads. To the forward end of these cross-heads are attached the saws, which extend forward in the direction of the buck, and are of sufficient length to operate 60 with the stroke of the cross-head, and so that the ends shall not be withdrawn from the timber or wood being sawed.

The letter G represents the uprights or standards, mortised or otherwise secured in the upper side beams of the frame, and have journaled in their upper portion the transverse shaft H, and on the upper facing of this shaft, at both ends, are fixed the upright standards or journal-boxes, or their equivalents, for the 70 purpose hereinafter stated; and one end of the shaft H extends through its upright and has attached thereto a lever, as hereinafter described.

The letter I represents a lifting-lever journaled in the uprights on the shaft H, and it consists essentially of the handle *f*, the loop *g*, and connecting-bar *h*, fastened to a staple, *h'*, in the cross-section of the carriage-frame, substantially as seen in Fig. 1 of the drawings.

The letter K represents the clamping-bar, secured to the transverse shaft H in any suitable manner, and extending therefrom in the direction of the buck, where it is made of suitable shape to grasp or clamp whatever is being 95 sawed. This clamping-bar may be made of the shape substantially as shown in Fig. 4 of the drawings, so as to straddle the timber at each end on the buck and prevent the stick from tilting when one saw reaches through before the other.

The letter *i* represents the buck or rest on

which the timber or stick of wood rests while being sawed.

The letter K^2 represents the lever fixed to the end of the shaft H , and having on its inner 5 side the spring-pawl k , engaging with stationary ratchet l , fixed to the upper outside of the upright, substantially as seen in Fig. 1 of the drawings.

The operation of our improved machine is 10 as follows: By withdrawing the pawl from engagement with the ratchet and raising the lever the shaft H is reversed, which lifts the clamping-bar until it strikes the extremity of the loop in the lever, when the saws, with 15 their carriage, are raised to any desired height in order to admit the timber or stick of wood to be placed in the buck. The lever is now brought down until the saws stop on the stick, and until the clamping-bar rests on the stick, 20 when, by a pressure upon the lever, the desired security may be given to the stick in the buck and locked in position by the engagement of the spring-pawl with the rack. Then by applying the power to the crank or other appliance 25 fixed to the driving-shaft the sawing may be proceeded with.

Should it be desired at any time during the progress of the saws through the material to lift them from engagement therewith, the handle 30 of the lifting-lever h is drawn back, which elevates the loop in the lever, which, through the instrumentality of the connecting-bar, lifts the carriage, with the saws, from the cuts, while the sticks remain securely clasped in the rests. 35 It will be observed that the loop of the lift-

ing-levers is so arranged that when the clamping-lever is drawn upward it engages with the loop and lifts the carriage, with the saws, to any desired height, where they may be retained and locked by means of the pawl or ratchet. 40

To the forward end of the standards of the frame are journaled wheels, and to the rear of the frame are fixed handles, in order that the machine may be moved from place to place as desired. 45

A joint may be made in the saw-carriage E at or near where the staple is located, so as to let up or down one of the saws.

We are aware that it is not broadly new with us to construct a drag-sawing machine with a 50 buck for supporting a stick of wood and means for clamping the same in position during the process of sawing; but

What we claim as our invention, and desire to secure by Letters Patent, is—

The combination, with a sawing-machine frame constructed with the uprights G and bucks i , of a transverse shaft, H , having at one end a lever, K^2 , with spring-pawl k , the fixed ratchet l , and clamping-bar K , substantially as and for the purpose set forth. 55

In testimony whereof we affix our signatures in presence of witnesses.

ANDREW J. SMITH.

JASPER NEWTON SMITH.
